UNITED STATES PATENT OFFICE.

EUGENE PHELPS, OF PITCHFORK, WYOMING.

CAN-OPENER.

1,261,284.

Specification of Letters Patent.

Patented Apr. 2, 1918.

Application filed April 11, 1917. Serial No. 161,298.

To all whom it may concern:

Be it known that I, EUGENE PHELPS, a citizen of the United States, residing at Pitchfork, county of Park, State of Wyoming, have invented a certain new and useful Improvement in Can-Openers, of which the following is a specification, reference being had therein to the accompanying drawings.

10 My invention relates to can openers of the type commonly employed for opening sealed tins and the like and has for its object a new and improved device for this purpose. The opener embodying my invention is especially 15 designed to sever one end from the can by removing a narrow strip of metal from its periphery adjacent the top so that there are no inwardly projecting flanges or burs and the entire contents of the can may be 20 moved without injury. A further object of my invention is to provide an opener by which a clean cut without jagged or rough edges may be produced. A still further object of my invention is to so arrange the 25 device that it may be made very quickly and cheaply and by which a can may be opened very simply and easily.

My invention will be fully understood from the following description when taken 30 in connection with the accompanying drawings and the novel features thereof will be pointed out and clearly defined in the claims at the close of this specification.

In the drawings, Figure 1 is a view of a 35 device embodying my invention and of a portion of a can, the top of which is being severed.

Fig. 2 is a view showing the can opener in closed position.

40 Figs. 3 and 4 are views in perspective of the can opener members.

Fig. 5 is a plan view of the cutting and guiding end of the member shown in Fig. 4.

Figs. 6 and 7 are sections on line 6—6 and 45 7—7 respectively of Fig. 3.

Fig. 8 is an end view of the device as viewed from the left in Fig. 1.

Having reference to the drawings, there is 50 shown a can opener embodying my invention which comprises a pair of members 11 and 12 connected by a pivot 13. The member 11 has a cutting slot 14 through which the blade 15 of the member 12 passes, the sides of which form shearing surfaces and guides 55 with which the blade of the member 12 co-

operates. The slot 14 terminates near the end of the member 11 a portion of the material of the member 11 being left at the end to prevent the member from spreading and widening the slot.

The member 11 is preferably formed from a flat strip of steel which is bent along a longitudinal medium line to form a U-shaped member having a pair of substantially parallel sides 16 and 17 and is curved lengthwise as shown. At the end of the member 11 adjacent the cutting slot 14 is a guide 18 comprising a lateral extension which is bent into the shape shown in Fig. 8 and extends slightly beyond the cutting edges of the member 11. The guide is preferably shaped as shown and is arranged so that the edge or bead 20 of a can 21 will fit between the guide 18 and the member 11 as is indicated in Fig. 8.

The coöperating member 12 consists of a handle portion 22 and the blade 15 the whole being preferably formed from a flat strip of steel. The handle portion 22 is of U-shape in cross section and is connected with the blade 15 by a shank 24 which is curved to a W-shape as shown in cross section in Fig. 7 and is provided with a rib 25 which extends from the ridge of the U-shaped handle 22 to the opposite side of the blade 15. The blade 15 is formed by bending the sides of the strips of steel stock oppositely to the sides of the U-shaped handle portion 22 so that it is composed of members 26 and 27 as is shown in Fig. 3. The stock is turned over abruptly and is compressed along the line of bend 28 so that the sides 26 and 27 lie closely adjacent each other. The shearing surface 29 of the blade 15 is formed by the edges of the members 26 and 27 and is arranged to lie parallel and in contact with the edges of the cutting slot 14 of the member 11. It will, therefore, be seen that the upper or non-cutting edge is the folded edge, and, therefore, when the blade is ground on the cutting edge there is no danger of the halves of the blade springing apart as would be the case if the folded edge was the cutting edge. The folded edge of the blade is thinner than the cutting edge to afford clearance for free 105 action.

The construction of the member 12 is important for it enables the member to be made from one piece of sheet steel so that it is light and inexpensive to produce. The con- 110

vex or U-shaped handle portion 22 affords a smooth gripping surface and the blade provides a shearing surface which may be repeatedly sharpened without becoming worn out. Furthermore the construction of the shank portion 24 is such that a strong and serviceable connection between the handle and blade is provided.

The blade 15 of the member 12 extends beyond the guide 18 of the member 11 when the device is closed as shown in Fig. 2 and the end of the blade is sharpened so that the metallic can may be readily punctured by it. A spring 30 is secured to the member 11 and engages with the inner surface of the member 12 thereby tending normally to hold the handles and blades in open position. In the drawings, I have shown the connection of the spring with the member 11 by forming a hook at the end of the spring and uniting it under a pair of projections 40 struck up from the handle. At 32 is a link which is connected to the member 12 by an eye 33 formed of a portion of the stock of which the member is made. The link 32 is adapted to engage with a suitable hook 34 formed in the member 11 to hold the device shut when not in use and when used as a punch to form a starting hole.

The device embodying my invention provides a ready means for opening a can whether of cylindrical shape or flat sided by inserting the point of the blade 15 through the periphery of the can at a point closely adjacent the one end. The member 18 extends over the edge of the can and forms a guide by the aid of which a narrow slot may be readily formed about the periphery of the can and its top severed. The shearing members form two parallel cuts and the slot which is produced provides plenty of room for the blade 15. By making the shearing surface of the blade thicker than the folded edge all possibility of cramping is prevented and a ready and easy means for opening a can is provided.

Copies of this patent may be obtained for five cents each, by addressing the "Commissioner of Patents, Washington, D. C."

What I claim is:

1. The improved can opener comprising a pair of members pivoted together and forming cutters, one of said members being formed from sheet metal and having a handle portion of U-shaped cross section, and a blade consisting of two members each of which has one side face in contact with a side face of the other, said blade being formed by folding the sheet metal in the reverse direction from that in which the metal forming the handle is folded.

2. The improved can opener comprising a pair of members pivoted together and forming cutters, one of said members being formed from sheet metal and comprising a handle which is of U-shaped cross section, a blade consisting of two contacting members formed by folding the sheet metal in the reverse direction from that in which the metal forming the handle is folded, and a shank connecting the said blade and handle together which is substantially W-shaped in cross section.

3. The improved can opener comprising a pair of members pivoted together and forming cutters, one of said members being formed from sheet metal and having a handle portion of U-shaped cross section, and a blade consisting of two contacting members formed by folding said sheet metal sharply together for a portion of its length, the edges of said members forming the cutting edge, and the folded edge forming the back of the blade.

4. The improved can opener comprising a pair of members pivoted together and forming cutters, one of said members consisting of a sheet of metal which is formed to have a U-shaped cross-section, and having a cutting slot near one end, and an extension at one side folded over to form a guide adjacent said slot.

In testimony whereof I affix my signature.

EUGENE PHELPS.
